UNITED STATES PATENT OFFICE.

JOHN W. CHERRY, OF CUMRO, NEBRASKA.

COMBINED JACK AND WIRE STRETCHER.

Application filed December 1, 1925. Serial No. 72,534.

To all whom it may concern:

Be it known that I, JOHN W. CHERRY, a citizen of the United States, residing at Cumro, in the county of Custer and State of Nebraska, have invented certain new and useful Improvements in Combined Jacks and Wire Stretchers, of which the following is a specification, reference being had to the accompanying drawings.

10 This invention relates to lifting jacks, and particularly to a lifting jack of the type wherein a worm is used for lifting the standard of the jack.

15 The general object of the invention is to provide a combined lifting jack and wire stretcher which may be used for either of these purposes and which may also be used for stretching wire fences.

20 A further object in this connection is to provide a jack of this character which is simple, strong and thoroughly effective for the purpose and which is provided with means whereby the load may be engaged with the standard of the jack at any desired 25 height.

A still further object is to provide a lifting jack which, as before stated, may be used as a stretcher or tightener provided with means whereby, after the wire has been 30 stretched a certain definite amount, the stretched wire may be held and a new hold taken to still further stretch the wire.

My invention is illustrated in the accompanying drawings, wherein:

35 Figure 1 is a side elevation of my combined jack and wire tightener shown in use for tightening fence wire;

Figure 2 is a like view to Figure 1 but showing one side of the casing removed;

40 Figure 3 is an elevation showing my device used as a jack;

Figure 4 is a vertical section on the line 4—4 of Figure 3;

45 Figure 5 is a vertical section on the line 5—5 of Figure 3;

Figure 6 is a vertical section on the line 6—6 of Figure 3;

Figure 7 is a section on the line 7—7 of Fig. 6;

50 In Figure 3, I have illustrated the device as used as a jack. Referring to this figure, 10 designates a base, as it may be termed, upon which is erected the casing of the jack, this casing consisting of the two side plates

55 11, the end plate 12, and the end plate 13. These are all riveted to each other or other-

wise attached. The casing at its upper end is laterally enlarged, as at 14, and enclosed therein, and operating upon a pivot 15 is a skew gear 16. Operating through the casing and bearing against the rear wall 13 is the standard 17 of the jack which is formed upon one edge face with the skewed rack 18 with which the skew teeth of the gear 16 engage.

The upper end of this standard 17 is angularly bent, as at 19, and formed upon one face of this standard is the fixed jaw 20 and the pivoted clamping jaw 21 which has a serrated rounded face. The lower end 70 of the casing is open and the base plate 10 is rectangular in form to leave a rectangular opening through which the standard is projectible. The casing plates 11 adjacent the base 10 are formed to provide the outwardly 75 projecting hook 22, the two walls of the casing being brought together and welded or otherwise engaged, and above this hook the walls of the casing are formed to provide the two outwardly projecting lugs 23. 80

Riveted or otherwise attached to the casing walls 11 is the strap 24 which extends laterally across the casing at the lower portion of the enlarged part 14 and is then extended downward and formed with a bearing 25 through which the shaft 26 extends. This shaft inward of the bearings is formed with a collar 27 and carries upon it the worm 28 which engages with the skew gear 16. A strap 29 is riveted or otherwise attached to the casing and extends across the end thereof and forms a bearing for the inner end of the shaft 26. The shaft 26 may carry a handle attached thereto but, as illustrated, is reduced to provide a square head 30 and a handle 31 is formed with a square socket to engage said head whereby the shaft 26 may be turned. The strap 29 is shown as carrying upon it the fixed jaw 32 and the double pivoted serrated jaws 33, the jaw 32 being undercut and either jaw 33 moving into the undercut portion and camming against the same. The double jaw or grip 33 allows the grip to be turned either way, which is particularly necessary where the device is used as a wire stretcher and it may be desired to clamp either end of the wire within the gripping device formed by the parts 32 and 33.

110 Mounted upon the shank or standard 17 for adjustment thereon is an approximately rectangular collar 34 which has a length

such that when the collar is disposed in a plane at right angles to the longitudinal axis of the standard 17, the collar may be moved up and down upon the standard 17. 5 One end of this collar is formed with a hook 35 or other like support. The opposite end of the collar is formed with a latch 36 which is adapted to engage between the teeth of the rack 18 and is formed with the projecting lug 37 constituting a handle. A flat spring 36^a fastened to collar 34 supports the latch 36 and keeps it in place. It will be seen that when this collar is disposed in an inclined plane, the latch 36 will engage between two of the teeth 18 and the collar will be jammed upon the standard and held from any downward movement, that is, movement toward the casing. The latch 36 is somewhat inclined so as to conform to the shape of the 20 skew teeth on the rack 18.

When it is desired to adjust the collar 34 upon the standard 17, it is only necessary to turn the tooth 36 by means of the handle 37 a slight distance to get it out of the space 25 between two teeth 18 and then the collar may be adjusted up and down upon the standard. The collar 34 with its hook 35 is adapted to support a load and then the standard 17 may be shifted vertically by 30 means of the shaft 26 to any desired extent to raise the load. The collar 34 may be shifted up or down the standard so as to accommodate loads of different heights in cases where the load is lower than the upper 35 end of the standard 17. It is possible with this device to lift a load which is initially close to the ground to a relatively considerable height by first lowering the collar 34 to its lowest position, engaging the load, 40 lifting the standard of the jack to its highest position, carrying with it the load, then supporting the load on timbers, and then lowering the standard of the jack until the upper end of the jack can get beneath the load and 45 again lift the jack.

It is to be particularly noted that the hook 22 is formed by an extension of the two side walls 11, these extensions of the two side walls being brought together in convergent relation and then welded or otherwise engaged with each other. This leaves 50 an aperture 29^a at the base of the hook which is in line with the space between the two lugs 23. These lugs 23, when the device is used as a wire stretcher, are adapted 55 to bear against the post A, as shown in Figure 1, and thus permit the wire B to have free passage along the face of the stretcher or jack and through the space 29^a and immediately in front of the post, whereas without these lugs 23 there would be great liability of the wire striking against the post and becoming bound thereby.

When it is desired to use the device as a 60 wire stretcher, it is disposed horizontally

and the hook 22 is placed around a post or the casing 11 is otherwise anchored in place. The wire is passed through between the fixed and movable jaws 20 and 21 and is clamped thereto after the standard 17 has been extended as much as possible. The shaft 26 is then rotated to draw the standard inward and, of course, draw the wire inward with it, and if the full stroke has been given of the standard 17 and more stretch is required 70 for the wire, the wire is engaged between the jaws 32 and 33 after one stretch has been given to it, then the member 17 is again extended, again engaged with the wire by means of the jaws 20 and 21, and again drawn inward into the casing 11 and the free end of the wire again taken up between the jaws 32 and 33. Thus any desired stretch 80 may be given to the wire. It is also possible to engage the hook 22 with an anchor and engage the angular end of the standard 17 with wire fencing, for instance, in any obvious and well known way and then retract the standard 17 into the casing, thus drawing 85 up the wire fencing.

The use of this device as a wire stretcher is made particularly possible because of the fact that both ends of the casing are open. This will also permit the hook 35 to be inserted beneath an object to be lifted and then the shaft 26 turned to cause the projection of the standard in a direction to press against the ground and thus cause the raising of the casing relative to the standard. Of course, the skew gearing will hold the standard set 90 against any strain and will also permit the standard to be released slightly when the device is used as a wire stretcher in case the wire is stretched too tight without any necessity of releasing the wire and re-tightening.

While I have illustrated certain details of construction which I have found to be particularly effective in practice, I do not wish to be limited thereto as this might be 100 changed in many ways without departing from the spirit of the invention as defined in the appended claims.

I claim:—

1. A jack and wire stretcher of the character described including a casing open at opposite ends, the casing being provided at one end with an outwardly projecting portion, a standard operating longitudinally through the casing and having a rack in one edge, one end of the standard having wire clamping means, means for longitudinally shifting the standard comprising a gear wheel having toothed engagement with the rack teeth of the standard, and a worm carried by the casing and engaging said gear wheel and having means whereby it may be manually operated.

2. A wire stretcher and jack of the character described comprising a casing open at 115

70

- opposite ends, a standard operating through the casing and toothed on one edge, a gear wheel mounted within the casing and engaging the teeth of the standard, a shaft 5 operatively supported in bearings on said casing and extending at an angle to the longitudinal axis of the casing and having a worm engaging said gear wheel, the casing at one end being provided with a relatively wide face and the casing and the outer end of the standard being each provided with a wire clamp, and the outer end of the casing being provided with an outwardly projecting anchor and with spacing lugs 10 disposed above the anchor.
3. A wire stretcher and jack of the character described comprising a casing open at opposite ends, a standard operating through the casing and toothed on one edge, the teeth 15 being skewed, a skew gear mounted within the casing and engaging the teeth of the standard, a shaft operatively supported in bearings on said casing and extending at an angle to the longitudinal axis of the casing and having a worm engaging said skew gear, the casing at one end being provided with a relatively wide base, the opposite end of the standard being formed with an outwardly bent portion having wire 20 clamps and the first named end of the casing being provided with an outwardly projecting hook constituting an anchor and with spacing lugs disposed just above the anchor.
4. A combined jack and wire stretcher of 25 the character described comprising a casing open at opposite ends, a standard longitudinally shiftable through the casing, man- ually operable means mounted upon the casing for shifting said standard, the casing being provided at one end with an outwardly projecting anchor, the central portion of the anchor adjacent the wall of the casing being apertured, spaced spacing lugs disposed inward of the anchor and between which a stretched wire may pass, the extremity of the standard remote from the anchor being angularly bent and provided with a wire-engaging clamp, and a wire-engaging clamp mounted upon the casing.
5. A combined jack and wire stretcher 30 comprising a casing having opposite side walls and end walls defining a longitudinally extending passage, and a standard operating through said passage and having skew teeth, a skew gear mounted between the side walls of the casing and engaging the skew teeth of the standard, a worm operatively mounted upon the casing and engaging said teeth of the skew gear, the lower end of the side walls of the casing being extended outward and toward each other to constitute a hook, there being an opening between the two side walls and the base of said hook, a pair of lugs extending out from the side walls just inward of the hook and constituting spacing means, the outer end of the standard being angularly bent beyond the side edge of the casing and being provided with wire-clamping means and the side wall of the standard being provided 35 with wire-clamping means.

In testimony whereof I hereunto affix my signature.

JOHN W. CHERRY.
